UNITED STATES PATENT OFFICE.

EDWARD W. MCCORMICK, OF BRIDGEPORT, CONNECTICUT.

STRAIGHT-WAY VALVE.

SPECIFICATION forming part of Letters Patent No. 225,229, dated March 9, 1880.

Application filed January 8, 1880.

To all whom it may concern:

Be it known that I, EDWARD W. MCCORMICK, of Bridgeport, Connecticut, have invented certain Improvements in Straight-Way Valves, of which the following is a specification.

My improvements relate to devices for operating straight-way valves; and my invention consists in the combination, with a screw-valve stem, of two valve-disks united by a toggle-joint to a swivel inserted into the lower end of the valve-stem, by the operation of which the toggle-joint is extended or bent, and the valve-disks thrust outwardly against the annular valve-seats on opposite sides of the valve-chamber, or withdrawn therefrom, as the case may be, preparatory to being lifted by the continued rotation of the valve-stem.

In the accompanying drawings, representing a straight-way valve embodying my invention, Figure 1 is a side elevation of the valve, with a portion of the wall of the valve-chamber removed, for the purpose of exhibiting the valve-disks and the devices by which they are operated. Fig. 2 is a transverse section of the valve-chamber through the line *x x* on Fig. 1.

The drawings represent an ordinary straight-way valve, A, the valve-chamber *a* of which is provided upon its opposite sides with two annular valve-seats, *a'* and *a''*.

Two valve-disks, B and *b*, are forced outwardly, and hence against the valve-seats *a* and *a'*, respectively, by means of a toggle-joint which unites them, and which is composed of the levers C and *c*, which are, respectively, pivoted at one end to the valve-disks, and at the other to a swivel, D, axially inserted in the lower end of the screw-stem E, and keyed

therein by the screw *e*, which is inserted laterally through the lower part of the valve-stem, 40 and at its inner end engages the annular groove *d*, formed in that part of the periphery of the swivel D which is inserted in the lower end of the screw-stem.

The valve-chamber is surmounted by the 45 usual cap A', through which the screw-stem passes, and the valve is opened by unscrewing the valve-stem, which bends the toggle-joint and withdraws and lifts both of the valve-disks away from their seats, while the contrary motion of the valve-stem serves to lower the valve-disks and extend the toggle-joint, and thus thrust the valve-disks outwardly against their seats and close the valve-opening.

The area of the opening in the top of the 55 valve-chamber is such that when the cap is removed the screw-stem and the valve-disks attached thereto by the toggle-joint may be easily removed.

It will, of course, be seen that each valve- 60 disk, when resting upon its seat, serves as the abutment for the support of the toggle in delivering its thrust upon the valve-disk.

I claim as my invention in a straight-way valve—

The combination of the screw-stem E with the swivel D and toggle-levers C *c*, the free ends of which are, respectively, pivoted to two valve-disks, each provided with an annular valve-seat, substantially as shown and de- 70 scribed.

EDWARD W. MCCORMICK.
